UNITED STATES PATENT OFFICE.

DEXTER S. RICE, OF PORTLAND, MAINE.

IMPROVEMENT IN EASY-CHAIRS.

Specification forming part of Letters Patent No. 126,984, dated May 21, 1872.

Specification describing a new and Improved Easy-Chair, invented by DEXTER SILAS RICE, of Portland, county of Cumberland, State of Maine.

In the accompanying drawing, Figure 1 represents a side view of my improved easy-chair. Fig. 2 is a vertical section of the same.

Similar letters of reference indicate corresponding parts.

This invention relates to a new manner of locking the hinged back of an easy-chair at a suitable inclined position, and also to a novel arrangement of foot-rest for the same. The invention consists, first, in the use of a hook at the lower end of the arm-rest support to lock over a series of pins formed in the slotted side rails of the chair; and, secondly, in the arrangement of a jointed foot-rest, which, when not used, can be folded out of the way, and out of sight under the seat, and locked by a spring-catch.

A in the drawing represents the lower rigid part of a chair comprising the front and back legs, the front and back rails, and the side rails *a a*. B is the chair-back, connected by hinges *b b* with the chair-body A, said hinges being of suitable construction. The arm-rests C are pivoted at *d* to the chair-back, and are in front rigidly connected with the arm-rest supports D. The lower end of each post or support D has a curved or inclined or a straight notch cut into it, as indicated by dotted lines in Fig. 2, or carries a metallic lower piece having such notch. The lower part of the post D fits into a groove or slot of the side rail *a* underneath, upon one of a series of pins, *e e*, which are

transversely secured across the slot or groove of said rail. When the notched end of the post is locked to one of the pins *e*, as indicated, the chair-back will also be locked, and if the back is to be more or less reclined the post D is merely lifted off the pin *e* which held it, and locked to another further back or in front. By this means a very simple means of adjusting the chair-back is obtained. F is the foot-rest, composed of three or more boards hinged together, and the uppermost board hinged to the front of the chair. The lower board has supporting-braces *f* pivoted to it in slots, whereby it can be held more or less high above the floor. The whole foot-rest can be carried out, as in Fig. 1, and more or less inclined, by means of the braces *f*; or it may, when not used, be folded partly against the front, partly beneath the chair, as in Fig. 2, and locked in this position by a spring-catch, *g*.

Having thus described my invention, I claim as new and desire to secure by Letters Patent—

1. The hinged back B joined to the arm-rest C, and combined with the notched supports D, and with the pins *e* in the slotted rails *a*, as set forth.
2. The jointed foot-rest provided with the pivoted braces *f*, and arranged on a chair, in combination with the spring-catch *g*, substantially as herein shown and described.

DEXTER S. RICE.
